UNITED STATES PATENT OFFICE.

THOMAS R. McKNIGHT, OF AURORA, ILLINOIS, ASSIGNOR TO WESTERN WHEELED SCRAPER COMPANY, OF AURORA, ILLINOIS, A CORPORATION OF ILLINOIS.

AXLE-SKEIN AND SAND-COLLAR.

No. 821,729.

Specification of Letters Patent.

Patented May 29, 1906.

Application filed March 8, 1904. Serial No. 197,183.

To all whom it may concern:

Be it known that I, THOMAS R. McKNIGHT, residing at Aurora, in the county of Kane and State of Illinois, have invented certain new and useful Improvements in Axle-Skeins and Sand-Collars, of which the following is a specification, reference being had to the accompanying drawings.

My invention relates to axle-skeins, and has for its object to provide a new and improved axle-skein which will be capable of being applied to ordinary metal wheel-spindles after they are worn out, thereby providing a new spindle which serves the same purpose as the old one.

A further object is to provide adequate protection for the bearing-surface of the skein against sand and dirt, thereby making the axle especially well adapted for use on wheeled scrapers and other implements used in similar work and in other situations where there is great exposure to sand and dirt.

I accomplish these objects as hereinafter described and as illustrated in the drawings.

What I regard as new is set forth in the claims.

In the accompanying drawings, Figure 1 is a longitudinal sectional view. Fig. 2 is a section on line 2 2 of Fig. 1. Fig. 3 is a partial section on line 3 3 of Fig. 1. Fig. 4 is a partial section on line 4 4 of Fig. 1. Fig. 5 is a partial side view of the pipe-box; and Fig. 6 is a sectional view of the skein, illustrating the collars at the inner end thereof.

Referring to the drawings, 10 indicates an ordinary axle-spindle which projects from a squared axle 11 and is provided with a threaded end 12 to receive a nut 13 in the usual way.

14 indicates a skein which is adapted to fit upon the spindle 10 and is provided at its inner end with a squared portion 15, adapted to receive the squared portion 11 of the axle and to fit tightly thereupon. The skein 14 is somewhat longer than the spindle 10, so that its outer end may be brought flush with the outer end of said spindle, as shown in Fig. 1. It will be understood that the inner surface of the skein 14 is shaped to fit the spindle 10, so that it is supported thereby. The outer surface of the skein 14 is suitably

shaped to serve as a spindle for a pipe-box or sleeve 16, which is adapted to be fitted in the hub 17 of a wheel, as shown in Fig. 1.

The nut 13 is provided with a flange 18, which is somewhat greater in diameter than the internal diameter of the pipe-box 16, so that the nut 13 when in place on the screw-threaded portion 12 of the spindle 10 serves to hold all the parts together.

The pipe-box 16 is provided on its outer surface with a number of ribs 19, as best shown in Figs. 4 and 5, said ribs serving to secure the pipe-box in place and prevent its rotation in the hub. The inner ends of the ribs 19 terminate a short distance from the inner end of the pipe-box 16, thereby providing a projecting portion 20, as shown in Figs. 1 and 5. The projecting portion 20 of the pipe-box is adapted to fit into an annular recess formed by providing the skein 14 with an intermediate collar 21, as best shown in Fig. 1. The outer portion of said collar extends forward substantially parallel with the outer surface of the skein 14 and a short distance therefrom, so that an annular channel or recess is provided around the skein near its inner end which receives the projecting portion 20 of the pipe-box which fits therein and also has an end bearing therein, as shown in Fig. 1. The collar 21 thus forms an end bearing for the inner end of the pipe-box, which is protected from dust and dirt by the overhanging portion of such collar. Furthermore, as shown in Fig. 1, the hub 17 is arranged to extend over or inclose the collar 21, so that double protection is secured against admission of dirt to the bearing-surfaces.

As best shown in Fig. 1, between the collar 21 and its inner end the skein 14 carries a dished collar 22, the outer surface of which is convex, its inner surface being concave, as shown in Fig. 1. The collar 22 is set a short distance from the collar 21, forming a space or pocket 23 between said parts. Furthermore, the collar 22 is of somewhat greater diameter than the collar 21. That surface of the collar 21 which lies next to the collar 22 is beveled, as shown in Fig. 1, being approximately parallel with the inner surface of the collar 22, as shown. The pocket 23, there-

fore, is angularly disposed, its outer portion lying deeper in the hub than its inner portion. The hub is recessed to receive the collar 22, the latter being provided with angular lugs 24 at suitable points in its periphery, which serve as scrapers to clear out the dirt accumulating in the recess in the hub, and thereby prevent, to a considerable extent, such material from working in between said collar 10 and the hub. As shown in Fig. 2, the margins of the lugs 24 are inclined, so that they better serve to remove the dirt from the hub.

By the construction described I provide an effectual seal against the admission of sand 15 and dirt to the bearing-surface of the skein 14, since in order to gain access thereto the dirt must not only pass the pocket 23, but must also work down between the collar 21 and pipe-box 16, passing around the projecting end of said pipe-box.

I wish it to be understood that, broadly considered, my invention is not restricted to the use of both collars, although such construction constitutes a further improvement, 20 which is particularly covered in subsidiary claims.

By my invention I provide means whereby old worn-out axles may readily be renovated, and, further, I secure effectual protection 25 against the admission of sand and other gritty matter between the bearing-surfaces of the spindle. I wish it to be understood, moreover, that although my improved skein is designed particularly for application to 30 worn-out or otherwise-disabled spindles, it may also be applied to spindles in good condition, thereby securing the benefits of the protective features above described. I wish it to be understood, further, that except in so 35 far as they are particularly claimed my invention is not restricted to the details of the construction described, but includes, generically, the subject-matter of the broader claims.

40 That which I claim as my invention, and desire to secure by Letters Patent, is—

1. An axle-skein, consisting of a sleeve adapted to fit upon an axle-spindle, said sleeve having an external bearing-surface, a collar carried by said sleeve near the inner end thereof, and an intermediate collar carried by said sleeve, said collars being spaced a distance apart and said intermediate collar having an annular channel in the outer face thereof.

55 2. An axle-skein, consisting of a sleeve adapted to fit non-rotatably upon an axle-spindle, said sleeve having an external bearing-surface, a dished collar carried by said sleeve near its inner end, and a scraper carried by said collar.

3. An axle-skein, consisting of a sleeve adapted to fit non-rotatably upon an axle-

spindle, said sleeve having an external bearing-surface, a collar carried by said sleeve near the inner end thereof, and a scraper carried by said collar and adapted to scrape the wheel-hub.

4. An axle-skein, consisting of a sleeve adapted to fit non-rotatably upon an axle-spindle, said sleeve having an external bearing-surface, a collar carried by said sleeve near the inner end thereof, a scraper carried by said collar and adapted to scrape the wheel-hub, and an intermediate collar carried by 75 said sleeve, said collars being spaced a distance apart.

5. The combination of a sleeve open at both ends adapted to fit upon an axle-spindle, said sleeve having an external bearing-surface, a plurality of collars carried by said sleeve near the inner end thereof, said collars being spaced apart, one of said collars having an annular recess adapted to receive the end of a pipe-box, and a pipe-box adapted to fit into said recess, substantially as described.

6. An axle-skein, consisting of a sleeve adapted to fit upon an axle-spindle, said sleeve having an external bearing-surface, a 90 collar carried by said sleeve near the inner end thereof and having an annular channel in its outer face, and means for shielding said collar from dirt.

7. An axle-skein, consisting of a sleeve 95 open at both ends adapted to fit upon an axle-spindle and having means for engaging the axle, said sleeve having an external bearing-surface, a collar carried by said sleeve near its inner end, and a scraper carried by said collar and adapted to scrape dirt from the wheel-hub, in combination with a wheel having its hub countersunk to receive said collar, substantially as described.

8. An axle-skein, consisting of a sleeve 105 open at both ends adapted to fit upon an axle-spindle and having means for engaging the axle, said sleeve having an external bearing-surface, a dished collar carried by said sleeve near its inner end, a scraper carried by said collar and adapted to scrape dirt from the wheel-hub, in combination with a wheel having its hub countersunk to receive said collar, and means for preventing said sleeve from rotating, substantially as described.

9. An axle-skein, consisting of a sleeve adapted to fit upon an axle-spindle, said sleeve having an external bearing-surface, a collar carried by said sleeve near the inner end thereof and having an annular channel in 110 its outer face, and a second collar carried by said sleeve for shielding said channeled collar from dirt.

10. The combination of a sleeve adapted to fit upon an axle-spindle, a collar carried by 115 said sleeve near its inner end and having a re-

cess in its outer face, a pipe-box mounted on said sleeve, its inner end fitting in said recess, a hub on said pipe-box extending over said collar, and a second collar carried by said sleeve and extending out beyond said first-mentioned collar.

11. An axle-skein, consisting of a sleeve adapted to fit non-rotatably upon an axle-

spindle, said sleeve having an external bearing-surface, a dished collar carried by said sleeve near its inner end, and a peripheral scraper carried by said collar.
